UNITED STATES PATENT OFFICE.

RAYMOND C. PENFIELD, OF NEW YORK, N. Y.

APPARATUS FOR HANDLING BRICKS IN STACKED UNITS.

1,150,061.

Specification of Letters Patent. Patented Aug. 17, 1915.

Application filed January 12, 1912. Serial No, 670,826.

To all whom it may concern:
Be it known that I, RAYMOND C. PENFIELD, a citizen of the United States, and resident of New York city, county and State 5 of New York, have invented an Improvement in Apparatus for Handling Bricks in Stacked Units, of which the following description, in connection with the accompanying drawings, is a specification, like letters on the drawings representing like parts.

This invention relates to apparatus for lifting and transferring bricks in stacked units of a type having a series of spaced apart, parallel fingers adapted to enter the 15 passages in the lower part of the brick units, with provision to laterally grip the bottom brick lines and lift them along with the rest of the stack, the apparatus being adapted to deposit the stacked units and be withdrawn without disturbing the stacked formation.

A principal object of the invention is to provide a simple, compact construction for the purpose stated, wherein a relatively 25 movable member, shown as a lifting bail, is connected to lift the load on the parallel fingers after a limited relative yielding movement for operating the brick clamps, the connection from the bail to the fingers 30 being a direct one without the interposition of any levers, lever combinations, or other indirect mechanical elements.

A further feature of the invention relates to an improved arrangement, mounting, and 35 manner of adjustment of the compression springs between the brick engaging fingers and the lifting bail, so that the pressure from the lifting bail is directly transmitted from the equalizer bar carried thereby 40 through these springs to the frame which carries the brick engaging fingers, the backing for the springs having an improved adjusting means enabling the initial compression of the springs to be quickly and easily 45 set in adjustment as required.

The invention will be better understood from the following detailed description, taken in connection with the accompanying drawings, and will be thereafter pointed out 50 in the appended claims.

Referring to the drawings, Figure 1 is a rear elevation of the improved mechanism.

Fig. 2 is a front view thereof. Fig. 3 is a plan. Fig. 4 is a side elevation, and Fig. 5 is a detail of the clamping devices.

55

In the illustrative embodiment of the invention shown, a base bar or frame 1 is employed, of a length corresponding to that of the brick units to be handled, and to this bar are fixed a series of parallel, spaced apart brick engaging fingers 2, such space being slightly greater than the width of a brick and the length of these fingers being, as shown, approximately that of a standard brick, since the particular form of the invention herein shown is designed for lifting units with a thickness the length of one brick. The base bar or frame 1 has similar sets of upstanding portions 3, 4 symmetrically arranged at either side of its center 60 and to each set is fixed an upright framework 5 serving as a support for the tops of vertical, spaced apart, parallel guide bars 6, the lower ends of these bars fitting down into adjacent inner faces of the upstanding 65 portions 3, 4. The vertical bars 6 serve as guides for the bails 7 which extend forwardly over the fingers 2, as seen at 8, and rearwardly at 9 for connection to the equalizer bar. These bails are shown as provided 70 with anti-friction rollers 10 engaging the bars 6 at front and rear and are provided with depending extensions 11 fitted between the bars 6, these extensions having ears 12 75 extending rearwardly with anti-friction rolls 80 13 engaging the backs of the bars 6 at the lower portions thereof. The rearward extensions 9 of the bails 7 are connected by means of adjustable links 14 with upstanding projections 15 fixed to an equalizer bar 85 16, which extends the length of the base frame, the connections 14 being spaced apart substantially equal distances from the center of said bar. From this bar, connection is made to operate the brick clamping devices 90 in the respective fingers by means of rods 17, connected to bell crank levers 18 pivoted at 19 is a bracket 20 fixed at the rear of the base frame, there being springs 21 interposed between the equalizer bar 16 and 95 heads 22 on the rods 17 to accommodate irregular and uneven bricks and effect a substantially uniform clamping of all the 100 bricks. Stop nuts 23 on the rods 17 engag-

ing the bar 16 underneath prevent the springs 31 from drawing the rods too far upward. The downwardly extending shorter ends 24 of bell crank levers 18 are connected to rods 25 which have their other ends pivoted to lever arms 26 mounted on vertical pivots 27 in the fingers, these arms having rigid connection to other arms 28 to which the clamp plates 29 are pivoted, these plates being fitted in recesses 30 in a side of the fingers and being projected therefrom by the described connections as the lifting mechanism is raised to transport the brick units. Thus, as lifting impulse on the bail 7 raises the equalizer bar 16 by means of the connecting rods 14, the connections just described cause the moving of the clamp plates 29 out against the sides of the bricks between the lifting fingers to clamp them firmly against the adjacent fingers.

The principal lifting stresses are transmitted from the bails 7 through the equalizer bar 16 to the base frame 1 which carries the pivots 19 of the levers 18 which actuate the brick engaging fingers by means of stout compression springs 31 interposed between seats 32 on the equalizer bar and at their upper ends on heads 33 carried at the lower ends of adjusting screw bolts 34 threaded in bars 35 fixed to the uprights 5 which, as described, are secured to the base frame. The screw bolts 34 are hollow for the reception of guide rods 36 which extend up from the bottom seats 32 through the springs and through the centers of these bolts. The bolts 34 have their peripheries threaded for most or all of their length and provide an adequate range of adjustment for regulating the initial compression of springs 31. They may be clamped in adjusted position by set nuts 37 engaging the bars 35. As shown, the heads 33 are some little distance above the lower ends of the bolts 34, thus affording a centering guide over which the springs 31 are centered against the heads 33. The bails 7 at either side are connected to a common lifting bar 38 having connection, shown as a central eye 39 for receiving the hook of a lifting crane or the like.

The compression springs 31 are preferably adjusted so as to be under some little initial tension and thus keep the bails 7 drawn inward with the brick clamps moved within the recesses 30 in the fingers 2 and only yield to permit the relative movement of the bails which effects the operation of the brick clamps as the stress of the load is brought thereon in the lifting operation. The present construction is particularly advantageous in that it provides a straight line direct connection from the bails 7 to the equalizer bar 16 and a direct action of the equalizer bar upon the compression springs 31 against the backing bars 35, which form

a part of the main or base frame. The provision of the springs 31 at the opposite side of the slideable engaging portions of the bails and frame from the fingers 2, effects a balancing about this line of slideable engagement which may be termed the axis of lift, so that the bails with their depending portions move freely and without binding on the guides of the base frame, and the freedom of relative movement between these parts is still further promoted by the anti-friction rollers 10, 13. The provision of the hollow screw bolts 34 as backings for the springs affords a means of quick and easy adjustment of the tension of the compression springs as may be required under different conditions.

The structural details of my improved mechanism may be varied to a considerable extent without departing from the essential features as set forth, and I therefore do not desire to be limited to the illustrative form of such details shown, or in any other respect, except as set forth in the appended claims.

Having described my invention, what I claim as new and desire to secure by Letters Patent is:

1. An apparatus of the kind described, comprising a base frame having a plurality of brick engaging fingers extending laterally therefrom, provided with brick clamping means, said frame having two fixed upstanding portions, a vertically movable member mounted to slide on said upstanding portions, and having antifriction bearings thereon, an equalizer bar actuated by said sliding member, a plurality of individual yielding connections from said bar to the brick clamping means, and a balancing spring interposed between said bar and said frame.

2. An apparatus of the kind described, comprising a base frame having a plurality of brick engaging fingers extending laterally therefrom, provided with brick clamping means, said frame having two fixed upstanding portions, a vertically movable member mounted to slide on said upstanding portions, and having antifriction bearings thereon, an equalizer bar actuated by said sliding member, a plurality of individual yielding connections from said bar to the brick clamping means, a balancing spring interposed between said bar and said frame, and means to adjust the tension of said spring.

3. An apparatus of the kind described, comprising a frame having a set of brick engaging fingers provided with brick clamps at one side thereof, a bail in guided slideable engagement with said frame, an equalizer bar having individual connections to the respective clamps and with positive operating connection from said bail, a balancing

spring interposed between said bar and said frame, and means for adjusting the initial tension of said spring, comprising a nut threaded in the frame, having a head furthering a backing for the spring, and also formed to serve as a guide for a central rod extending through the spring.

In testimony whereof, I have signed my name to this specification, in the presence of two subscribing witnesses.

RAYMOND C. PENFIELD.
